SAFETY ATTACHMENT FOR SMOKERS

John R. Colvin, III, Philadelphia, Pa.

Application December 20, 1949, Serial No. 134,074

2 Claims. (Cl. 131—174)

1

This invention relates to a safety attachment for smokers, and more particularly to such an attachment wherein the lighted end of a cigarette may be extinguished voluntarily or involuntarily.

An object of this invention is to provide a safety attachment for smokers, wherein a cigarette may be rendered ineffective as a fire hazard when the smoker falls asleep while the cigarette is still burning.

Another object of this invention is to provide a safety attachment for smokers, wherein the cigarette is supported externally of the attachment for smoking and is urged interiorly of the attachment when the smoker intentionally or inadvertently releases his grip on the latter.

A further object of the invention is to provide a safety attachment for smokers, wherein a cigarette can be extinguished safely when an ash receptacle is not available, and when extinguished, be carried by the smoker in a neat, compact closure until a time when the extinguished cigarette can be disposed of.

A still further object of the invention is to provide a safety attachment for smokers which is simple in structure and cheap to manufacture.

Further objects of this invention will become apparent upon consulting the drawings in conjunction with the following specification.

In the drawings:

Figure 1 is a perspective view of the safety attachment of the present invention in association with a cigarette, the attachment being shown retracted;

Figure 2 is a perspective view of the assembled attachment and cigarette of Figure 1, with the attachment being shown extended;

Figure 3 is a side elevational view, with parts in section, of the assembly shown in Figure 2;

Figure 4 is a sectional view taken on the line 4—4 of Figure 3.

Referring now to the drawings, wherein like reference numerals have been used throughout the several views to designate like parts, there is shown the safety attachment of the present invention, generally indicated by the numeral 10, which includes a cylindrical, hollow casing 11 having one end open and having the other end closed, and a cylindrical holder 12 having one end open and the other end closed. The closed end of the holder 12 is positioned in aligned relation with respect to the open end of the casing 11, and the holder 12 is mounted in the casing 11 for extensible and retractile movements with respect to the latter. Disposed with-

2

in the open end of the holder 12 and secured thereto is a cigarette grip 13, there being a longitudinal bore 14 in the cigarette grip 13 for embracingly receiving and supporting a cigarette 15 therein. The cigarette 15 is positioned such that the lighted end thereof is spaced from the closed end of the holder 12 and the other end thereof projects beyond the open end of the holder 12. The peripheral wall of the holder 12 intermediate its ends is cut away, as indicated at 16, to provide a partially enclosed area for housing the portion of the cigarette 15 to be consumed during smoking and to permit the entrance of sufficient air thereto to support combustion. Spaced from the closed end of the holder 12 and located longitudinally of said holder about the periphery thereof are a plurality of guide fingers indicated by the numeral 17. Each of the guide fingers 17 extends toward the cigarette grip 13. Accordingly, the cigarette 15 may be positioned such that the portion adjacent the cigarette grip 13 is readily accessible to the mouth of the smoker, and the portion partially surrounded by the fingers 17 can be lighted. Extending outwardly from and fixedly secured to the closed end of the holder 12 is a ring-like flange 26.

Positioned exteriorly of the casing 11 and fixedly mounted longitudinally thereof is a resilient catch 18 which is movable into and out of engagement with the holder 12 to thereby position the latter in an extended position. The resilient catch 18 has one end fixedly secured to the peripheral wall of the casing 11 by means of rivets indicated at 19, and has the other end bent inwardly, as indicated at 20.

Referring to Figure 3, there is shown in broken lines the normal position of the resilient catch. The peripheral wall of the casing 11 is provided with a slot 21 for the insertion and withdrawal therethrough of the bent end 20 of the resilient catch 18.

Supported within the casing 11 and operatively connected to the holder 12 is a resilient member 22, which normally urges the holder 12 into a retracted position. One end of the resilient member 22, which is illustrated as a spring, is fixedly secured to the closed end of the casing 11 by means of a lug 23. The other end of the resilient member 22 is fixedly secured to a lug 24, the lug being fixedly secured to the flange 26.

With the safety attachment and cigarette in assembled relation, as shown in Figure 1, when it is desired to smoke the cigarette 15, the casing 11 is grasped by the hand of the smoker. While

so grasped, the smoker exerts an outwardly directed pull on the holder 12, such pull resulting in the holder 12 being urged to an extended position, as clearly illustrated in Figures 2 and 3. The resilient catch 18 is then pressed inwardly causing the bent end 20 thereof to extend through the slot 21 in the casing 11 and to engage the flange 26 carried by the holder 12 to thereby hold the holder 12 in an extended position. The resilient catch 18 is kept in its position of engagement with the flange 26, as the cigarette is lighted and smoked. When the resilient catch 18 is released, due to an intentional release thereof by the smoker, the holder 22 is urged into a retracted position and the lighted end of the cigarette 15 is completely enclosed. Accordingly, the cigarette 15 will be extinguished, due to the lack of a sufficient amount of air to support combustion.

Although only one embodiment of the invention has been shown, numerous modifications may be made without departing from the spirit of the invention as set forth in the appended claims.

What I claim is:

1. In a safety attachment for smokers, a casing having one end open and having the other end closed, a holder having one end closed and having the other end open, the closed end of said holder being positioned within the open end of said casing and mounted therein for extensible and retractile movements, the wall of said holder intermediate its ends having a partially enclosed portion for housing the portion of a cigarette to be consumed during smoking and permitting the entrance of sufficient air thereto to support combustion, gripping means disposed within the open end of said holder and secured thereto for embracingly receiving and supporting said cigarette longitudinally thereof with the end of the cigarette to be lighted spaced from the closed end of said holder and the other end of said cigarette projecting from the open end of said holder, a plurality of guide fingers extending toward said gripping means and spaced longitudinally of said holder at intervals about the periphery thereof, an annular flange disposed in end to end relation with respect to the closed end of said holder, a lug carried by said flange, resilient means carried by said casing and connected to said lug for

normally urging said holder into a retracted position to thereby extinguish said cigarette by oxygen deprivation, and hand actuatable means carried by said casing engageable with said flange for holding said holder in an extended position.

2. In a safety attachment for smokers, a casing having one end open and having the other end closed, a holder having one end closed and having the other end open, the closed end of said holder being positioned within the open end of said casing and mounted therein for extensible and retractile movements, the wall of said holder intermediate its ends having a partially enclosed portion for housing the portion of a cigarette to be consumed during smoking and permitting the entrance of sufficient air thereto to support combustion, gripping means disposed within the open end of said holder and secured thereto for embracingly receiving and supporting said cigarette longitudinally thereof with the end of the cigarette to be lighted spaced from the closed end of said holder and the other end of said cigarette projecting beyond the open end of said holder, a plurality of guide fingers extending toward said gripping means and spaced longitudinally of said holder at intervals about the periphery thereof, resilient means carried by said casing and connected to said holder for normally urging said holder into a retracted position to extinguish said cigarette by oxygen deprivation, and hand actuatable means carried by said casing engageable with said holder for holding said holder in an extended position.
